CLAIM

The ornamental design for a surgical generator, as shown and described.

DESCRIPTION

FIG. 1 is a perspective view of a surgical generator as seen from the front, top, and right side;

FIG. 2 is a top plan view thereof;

FIG. 3 is a front elevation view thereof;

FIG. 4 is a right side elevation view thereof;

FIG. 5 is a back end elevation view thereof;

FIG. 6 is a left side elevation view thereof;

FIG. 7 is a bottom plan view thereof;

FIG. 8 is a perspective view as seen from the front, top, and right side of a modified embodiment of the design shown in FIGS. 1-7;

FIG. 9 is a top plan view thereof;

FIG. 10 is a front elevation view thereof;

FIG. 11 is a right side elevation view thereof;

FIG. 12 is a back end elevation view thereof;

FIG. 13 is a left side elevation view thereof; and,

FIG. 14 is a bottom plan view thereof.

The broken lines in the figures illustrate unclaimed environment only and form no part of the claimed design.

1 Claim, 14 Drawing Sheets
